(57) **CLAIM**

What is claimed is the ornamental design for a power tool, as shown and described.

DESCRIPTION

FIG. 1 is a perspective view of the power tool;
FIG. 2 is a right side view of the power tool, the left side view is not shown as it is a mirror image of the right side view; and

FIG. 3 is a top plan view thereof;

FIG. 4 is a bottom plan view thereof;

FIG. 5 is a rear elevational view thereof; and,

FIG. 6 is a front elevational view thereof.

The broken lines are shown in the views for illustrative purposes only and form no part of the claimed design.
